UNITED STATES PATENT OFFICE.

HAROLD J. BELL, OF WOODBURY, NEW JERSEY, ASSIGNOR TO THE WELS-BACH INCANDESCENT GAS LIGHT COMPANY, OF NEW JERSEY.

INCANDESCENT GAS-BURNER.

SPECIFICATION forming part of Letters Patent No. 396,254, dated January 15, 1889.

Application filed March 21, 1888. Serial No. 267,987. (No model.)

To all whom it may concern:

Be it known that I, HAROLD J. BELL, a citizen of the United States, residing at Woodbury, in the county of Gloucester and State of New Jersey, have invented new and useful Improvements in Incandescent Gas-Lamps, of which the following is a specification.

This invention relates to a gas-lamp comprising a number of atmospheric gas-burners and incandescent devices; and it consists in certain peculiarities in the construction and relative arrangement of parts, as will be hereinafter more fully described and claimed.

In the annexed drawings, illustrating the invention, Figure 1 is a vertical section of an incandescent gas-lamp embodying my improvements. Fig. 2 is a horizontal section of the same on the line *x x*, and Fig. 3 is a similar section on the line *y y* of Fig. 1.

By referring to Fig. 1 it will be seen that the numeral 1 designates a gas and air mixing chamber, which is cylindrical in its lower part and flared or expanded on all sides in its upper portion. In the lower end of this chamber 1 may be screwed an internally and externally threaded union or coupling, 2, whereby said chamber can be secured to and supported on a gas-bracket; or the gas-bracket and the gas and air mixing chamber can be connected by any suitable means. As shown in Fig. 1, the lower end of the coupling or union 2 is closed by a plug 3, the gas-supply in this instance being introduced from above, as will be hereinafter described.

The upper end of the gas and air mixing chamber 1 is closed, except at openings 4, a number of which are provided in the top of said chamber for the insertion of the atmospheric gas-burners 5, which may be of any suitable construction, though I prefer a burner of the kind described in my application filed March 8, 1888, Serial No. 266,505. Each burner-tube supports a gallery, 6, which in turn supports a rod, 7, from which is suspended above the burner a mantle, hood, cap, or frame, 8, of incandescent material, and a glass chimney, 9, is placed on each gallery around the burner and incandescent device.

A depending vertical gas-supply tube, 10, may be passed into the gas and air mixing chamber 1, and be secured therein so as to

support said chamber from above; or, as before mentioned, the gas and air mixing chamber can be supported from below on a gas-bracket, through which gas can be supplied, 55 in which event the upper end of the tube 10 may be closed by a plug or other suitable means.

The lower end of the gas-tube 10 is open and passes through a disk, 11, that is secured 60 horizontally in the lower part of the gas and air mixing chamber 1, said disk being provided with a series of perforations, 12, for the upward passage of gas into the gas and air mixing chamber. In the lower part of the 65 gas and air mixing chamber 1 is formed a series of lateral air-inlets, 13, and in order to control the quantity of air admitted through these inlets a movable band or collar, 14, is placed around the lower parts of the chamber, so as to be capable of covering or uncovering the air-inlets, said band or collar being provided with a series of openings, 15, that are capable of registering with said inlets when the band or collar is properly rotated.

A gallery, 16, of metal, glass, or other suitable material, is adjustably supported on the gas and air mixing chamber 1 by means of a set-screw, 17, that engages a collar, 18, 80 formed on or attached to the lower part of said gallery. The gallery or globe-holder 16 supports a glass globe, 19, that surrounds the entire group of burners and incandescent devices. This gallery or globe-holder 16 is preferably closed or imperforate at its bottom, as shown, so as to compel the outer-air supply to be obtained from over the top of the globe and thus become heated on its way down around the several chimneys to their lower 90 ends, through which it passes upward around and through the incandescent mantles.

On the tube 10, above the gas and air mixing chamber, is an adjustable ring, 20, that supports a metallic hood, 21, having a metallic chimney, 22, at its upper end. The ring 20 may be held in place by a screw, 23, or otherwise, so as to be adjustable vertically on the tube 10, and this ring 20 thus affords an adjustable support for the hood 21, which is provided with a bottom, 24, that rests on said ring.

In the hood-bottom are a number of circular openings, 25, that receive the upper ends of the glass chimney 9, which surround the suspended incandescent devices. In the metal hood-chimney 22 is secured a transverse bar, 26, having midway its length a centrally-enlarged slot, 27, that surrounds the tube 10, and on the upper portion of this tube, above the slotted bar 26, is a laterally-projecting pin, 28, over which the slot 27 in the bar 26 can be passed when the hood is raised, so that by lifting the hood 21 and chimney 22 until the slotted bar 26 clears the pin 28, and then turning the hood and chimney a quarter-revolution, they can be supported on said pin while the chimneys 9, surrounding the burners, are being removed and replaced, or whenever it is desired to obtain access to the burners and incandescent devices.

The gas and air supplied to the mixing-chamber 1 passes to the group of burners supported by said chamber around the central tube, 10, and when ignited the several mantles or frames 8 of refractory material are heated to incandescence. The open upper end of the globe 19 admits a quantity of air, which, in passing downward around and between the group of chimneys 9, becomes heated before entering said chimneys at their lower ends, and a large quantity of hot air is thus distributed on the surfaces of the incandescent devices, so as to increase their efficiency in the production of light.

By employing a closed globe-holder, 16, and causing the upper ends of the chimneys 9 to penetrate the bottom of the metallic hood 21, as shown, the air admitted over the upper edge of the globe 19 is compelled to pass down around the several chimneys, and thus become thoroughly heated before gaining access to their lower open ends.

It will be observed that the various parts of the lamp are readily detachable and adjustable for facilitating the removal and replacement of parts when required, and afford convenient means for grouping a number of gas-incandescents in a cluster.

What I claim as my invention is—

1. In an incandescent gas-lamp, the combination, with a gas and air mixing chamber and a number of gas-burners supported on and communicating with said chamber, of a central gas-tube passed vertically through said chamber, and a perforated disk surrounding the open lower end of said tube, substantially as described.

2. In an incandescent gas-lamp, the combination, with a number of atmospheric gas-burners arranged in a group or cluster and a corresponding number of incandescent devices suspended above said burners, of a chimney surrounding each incandescent device, a vertically-adjustable globe surrounding the entire group or cluster of burners and incandescent devices, and a vertically-adjustable metallic hood and chimney supported above the several incandescent devices and their surrounding chimneys and globe, but penetrated by said chimneys, substantially as described. 70

3. In an incandescent gas-lamp, the combination of a number of atmospheric gas-burners, a corresponding number of incandescent devices suspended above said burners, chimneys surrounding said incandescent devices, 75 a globe surrounding all the burners and chimneys, and a globe-holder having a closed or imperforate bottom, substantially as described.

4. In an incandescent gas-lamp, the combination of a gas and air mixing chamber, a 80 number of burners supported by said chamber, a central tube having an adjustable collar, and a metal hood supported on said collar above the gas-burners, substantially as described.

5. In an incandescent gas-lamp, the combination, with a group of gas-burners and incandescent devices and their chimneys, of a central tube having a collar, 20, and pin 28, and a hood, 21, supported on said collar, and 90 having a slotted bar, 26, adapted to engage the pin 28, whereby the hood can be raised and supported clear of the burner-chimneys, substantially as described.

6. In an incandescent gas-lamp, the combination of a gas and air mixing chamber, a number of gas-burners supported by said chamber, incandescent devices suspended above the burners and surrounded by chimneys, an adjustable globe surrounding the entire group of burners and incandescents, and an adjustable metal hood suspended above but penetrated by the burner-chimneys, substantially as described. 95

In testimony whereof I affix my signature in 105 presence of two witnesses.

HAROLD J. BELL.
